UNITED STATES PATENT OFFICE

SHERMAN T. ALLEN, OF BEVERLY HILLS, CALIFORNIA

LOCK AND LATCH

Application filed January 30, 1931. Serial No. 512,396.

This invention relates to door latches, and has for an object the provision of an improved type of latch and lock adapted to be used advantageously in conjunction with various types of closures, such as ordinary inside and outside doors, office doors, and the doors used upon vehicles.

The latch of the present invention constitutes an improvement over that set forth in my copending application Serial No. 427,796, filed February 12, 1930.

A more detailed object is the provision of a door latch wherein the movable portions are carried by an integral basket structure adapted to be let into a notch in the edge of a door, and to be secured to the door by means of escutcheon plates carried by the basket and movable relatively thereto only in directions perpendicular to the plane of the door, so that when the escutcheon plates are clamped securely against the faces of the door, removal of the latch and lock structure is prevented.

Another object is the provision of a latch and lock wherein a single bolt serves as both the latching and the locking bolt, and wherein the means for locking the bolt in extended position, so as to prevent opening of the closure with which the device is associated, by others than authorized persons, is carried by and is normally retained within the shaft whereon the doorknobs are mounted.

Another object is the provision of a latch and lock having the above described characteristics, and which is also provided with means for retaining the bolt in withdrawn position when the closure is moved from closed position, thereby eliminating the annoyance frequently caused by the protruding end of the bolt when the door is open.

Another object is to provide a latch and lock as described, in which the knob shaft is journaled solely in the basket structure, and not in the escutcheon plates as in the case of the conventional latch and lock.

A further object is to provide a door latch and lock having key-operated means for releasing the lock from the outside of the door, and in which this key-operated means auto-

matically becomes disengaged from the locking bolt when the device is unlocked, thereby permitting continued rotation of the key-operated means to that position in which the key may be removed therefrom without again locking the device.

The invention possesses other objects and advantageous features, some of which, with those enumerated, will be set forth in the following description of the invention's particular embodiments which are illustrated in the drawings accompanying and forming a part of the specification.

Referring to the drawings:

Fig. 1 is a view in side elevation of a portion of a door and its associated frame, with a latch and lock of my invention operatively installed therein, portions of the structure being broken away to disclose some of the internal mechanism.

Fig. 2 is a vertical sectional view taken transversely through the device, upon the line 2-2 of Fig. 1.

Fig. 3 is a horizontal sectional view taken upon the line 3-3 of Fig. 2.

Fig. 4 is a vertical sectional view taken in the plane of the door upon the line 4-4 of Fig. 3.

Fig. 5 is a transverse vertical sectional view taken upon the line 5-5 of Fig. 4.

Fig. 6 is a vertical sectional view taken in the plane of an automobile door, and showing in side elevation a modified form of the lock and latch of my invention, portions of the figure being broken away to reduce its length.

Figs. 1 to 5 inclusive show one modification of my improved and simplified latch and lock mechanism operatively mounted within a door 11 which is hingedly mounted in cooperative relationship with a door frame 12 in the usual manner. The supporting structure wherein the operative parts of the latch are mounted is in the form of a basket 13 which comprises rigidly, and preferably integrally, joined side walls 14 held in spaced parallel relationship by inner and outer end walls 16 and 17, respectively, and preferably an auxiliary web 18 extending across the space 19 between the side walls.

14, this web 18 being parallel to the end walls 16 and 17. On the inner face of each of the side walls 14, and spaced slightly from the outer end wall 17, beads 21 are provided, 5 these two beads being in alignment with each other, as best shown upon Fig. 3.

A bolt 23 is reciprocably mounted for movement longitudinally with respect to the basket structure 13, being slidably disposed 10 within aligned apertures 24 and 26 in the end wall 17 and the web 18, and this bolt 23 is continually urged outwards by means of a coil spring 27 which is under compression between the web 18 and a shoulder 28 on 15 the bolt 23. When the bolt 23 is moved by the spring 27 to its outer extreme of movement, its outer end projects far enough from the outer edge 29 of the closure 11 to be received within the socket 31 of a keeper 32 20 which is rigidly secured to the associated jamb 33 of the door frame 12. However, means are provided for retaining the bolt 23 in retracted position at all times when the door 11 is moved from closed position. 25 Guided for vertical movement between the beads 21 and the outer end wall 17 of the basket structure 13 is a retaining plate 36 having an enlarged aperture 37 therein, through which the bolt 23 extends. The bolt 23 is provided with an annular groove 38 adapted to come into registry with that portion of the plate 36 within which the aperture 37 is provided, when the bolt 23 is 30 fully retracted, permitting the upper edge 35 of the aperture 37 to enter the groove 38 and thus hold the bolt 23 against being thrust outwards by the spring 27. The plate 36 is continually urged toward that position in which the upper edge of the aperture 37 40 seats within the groove 38, by means of a coil spring 39 under compression between the upper edge of the plate 36 and a flange 41 extending inwards from the outer end wall 17. Hence, whenever the bolt 23 is retracted so as to permit opening the door 11, the plate 36 will engage the bolt 23 and prevent its being thrust outwards again until the plate 36 is moved to releasing position, 45 for which purpose a cam 42 is provided upon the lower edge of the plate 36. A rod 43 is slidably mounted in the side walls 14 of the basket structure 13, and has at least one end 44 projecting through the associated side wall far enough to engage the 50 jamb 33 as the door completes its closing movement, so as to push the rod 43 toward the left, as viewed upon Fig. 5. The cam 42 of the plate 36 seats within a notch 46 in the rod 43 when the plate 36 is in its 55 lowermost position, but the cam 42 and the notch 46 are so shaped that when the rod 43 is pushed as hereinabove described, the cam 42 will be forced out of the notch 46, thus moving the plate 36 upwards to remove 60 the upper edge of the aperture 37 from the 65

groove 38, whereupon the spring 27 may project the bolt 23 into latching position.

The inner end 51 of the bolt 23 is bifurcated, providing upper and lower legs 52 and 53, respectively, adapted to pass on opposite sides of the knob shaft 54. This shaft comprises a central barrel portion 56, which is of tubular construction, inasmuch as it has an axial bore 57 therethrough. The barrel 56 is journaled within aligned holes 58 in the side walls 14 of the basket structure 13, and is provided at each end with a tubular extension 59, each of which is adapted to receive the shank 61 of a knob 62 which is slidably receivable thereon. Each of these shanks 61 is provided with one or more projecting bosses 63 adapted to be received within complementary notches 64 in the associated end of the central enlarged portion of the barrel 56, 75 whereby rotary motion of the knob will impart similar motion to the remainder of the knob shaft 54. A lug 66 rigid with the central portion of the barrel 56 seats within a recess 67 in preferably the upper leg 52 of 80 the bifurcated end 51 of the bolt 23, so that when the shaft 54 is turned in counterclockwise motion, as viewed on Fig. 4, the bolt 23 will be retracted.

The enlarged portion of the barrel 56 is 85 provided with a transverse hole 71, which is blind at one end 72. A locking detent 73 is reciprocably mounted in this transverse hole 71, and is continually urged radially outwards from the barrel 56 by means of a 90 coil spring 74 which is under compression between the blind end 72 of the hole 71 and the inner end of the detent 73. The detent 73, however, is of such length that when it is retracted it is entirely contained 95 within the hole 71.

This hole 71 is so positioned in the barrel 56 that when the bolt 23 is extended the hole 71 is disposed substantially vertically. A socket 76 is formed in the upper surface of 100 the lower leg 53 of the bolt 23, in such position that it is in registry with the hole 71 when the bolt 23 is extended. Hence, the associated ends of the detent 73 and socket 76 move in opposite directions when the bolt 105 23 is being retracted, and for this reason locking of the bolt 23 in extended position with extreme rigidity may be attained by dropping the detent 73 into the socket 76.

Movement of the detent 73 with respect 110 to the barrel 56 may be accomplished by means of a locking shaft 77 which extends through the bore 57 of the knob shaft 54. This shaft 77 also passes through the hole 71 and through a hole 78 in the inner end 115 of the detent 73. This hole 78 is at least as large as the cross sectional area of the shaft 77, although that portion 79 of the shaft 77 which normally engages within the hole 78 of the detent 73 is flattened at one 120

side so that it is of substantially semi-circular cross sectional configuration, as best shown upon Figs. 2 and 4. Hence, rotary motion of the shaft 77 within the 5 knob shaft 54 is capable of causing movement of the detent 73, because when the arcuate side of the flattened portion 79 is turned toward the blind end 72 of the hole 71 the detent 73 will be drawn completely 10 into the hole 71, and when the flattened side of the portion 79 of the shaft 77 is turned toward the blind end 72 of the hole 71, the detent 73 will be pushed outwards from the hole 71 by its spring 74.

15 The locking shaft 77 extends completely through the knob 62, which is disposed upon the interior side of the door 11, and is provided with an auxiliary knob 81 which may be grasped by the fingers to permit rotary motion of the locking shaft 77 without turning the larger knob 62. An arcuate groove 82 is formed in the under surface of the knob 81, and receives a pin 83 which is rigid with the knob 62, the groove 82 being of such length that it permits substantially one-sixth ($\frac{1}{6}$) of a complete revolution of the locking shaft 77, and being so positioned in the knob 81 that when the knob 81 is turned to one extreme 30 of its motion with respect to the knob 62, the detent 73 will be fully extended, and when the knob 81 is turned to its other extreme of motion the detent 73 will be fully retracted.

35 The other end of the locking shaft 77 is provided with a shoulder 86, which preferably is formed by cutting away substantially one-half ($\frac{1}{2}$) of the shaft 77 adjacent the end, thereby leaving a flat face extending 40 substantially diametrically with respect to the shaft 77. A key-operated lock 87, preferably of conventional design, is mounted in the outside knob 88, this lock 87 being provided with a barrel 89, which may be turned 45 only by means of the proper key. The lock 87 is positioned in such a manner that its barrel 89 rotates about an axis offset from that of the locking shaft 77 a distance equal to substantially one-half ($\frac{1}{2}$) the diameter 50 of the shaft 77. A shoulder 91 formed on the inner end of the barrel 89 is adapted to cooperate with the shoulder 86 of the locking shaft 77, so as to permit withdrawal of the locking detent 73 when the barrel 89 is turned. 55 The shoulder 86 on the locking shaft 77 is disposed substantially vertically when the detent 73 is extended, and the shoulder 91 also is disposed vertically when the key whereby the barrel 89 may be turned 60 is removed from the barrel. Moreover, the parts are so proportioned and arranged that only the upper end of the shoulder 91 is adapted to engage the shoulder 86, and adjacent only the lower end of the latter shoulder, so that when the barrel 89 is turned, this

engagement between the shoulders will effect sufficient rotation of the shaft 77 to cause retraction of the detent 73, whereupon the shoulder 91 will become disengaged from the shoulder 86, permitting continued rotation of the barrel 89 through a complete revolution, so that the key may be removed therefrom. However, the locking shaft 77 ceases to rotate when disengagement between the shoulders 91 and 86 occurs, and remains 70 in that position in which the detent 73 is fully retracted until it is again turned to detent-extending position by means of the knob 82 upon the inside of the door. The purpose of this arrangement is to make it possible to unlock the door from the outside by means of the proper key and to remove the key without again setting the locking mechanism. In other words, the device can again be locked only by the conscious effort 85 of the operator by manipulation of the knob 81, which is accessible from only the inside of the door.

80 The latch and lock of the present invention is provided with escutcheon plates 96 and 97, which are of sufficient size to extend beyond the upper, lower and inner edges of the basket structure 13. The plates 96 and 97 may terminate short of the outer edge of the basket, or they may be provided with inwardly offset extensions 98 engaging the associated side walls 14 of the basket structure 13, as clearly shown upon Fig. 3. These offset extensions 98 are each provided with a groove 99 on the inner surface, within which 100 a complementary bead 101 on the outer surface of the associated side wall 14 seats. This engagement permits motion of the escutcheon plates 96 and 97 in a direction 105 perpendicular to their planes, but holds the escutcheon plates against movement within their respective planes and with respect to the basket structure. The same effect is attained by means of a plurality of stay bolts 102, the heads 103 of which are accessible 110 interiorly of the door, and the other ends of which are threaded into sockets 104 formed on the inner surface of the escutcheon plate 96 which is on the outside of the door. These stay bolts 102 pass through 115 suitably positioned holes 106 in the side walls 14 of the basket structure 13.

120 That end 44 of the releasing rod 43 which is engageable with the jamb 33, extends through the associated offset extension 98 of the escutcheon plate 96, so that the presence of the extension 98 does not interfere with the normal operation of release of the bolt 23 when the door is closed.

125 Instead of being fastened to the barrel 56, the shanks 61 of the knobs 62 are retained against axial movement with respect thereto by means of plates 111, one of which is pivotally mounted upon the interior surface of each of the escutcheon plates 96, 97. Each 130

of these plates 111 is adapted to drop by its own weight into the upper portion of an annular groove 112, which is provided in the shank 61 of the associated knob 62 when that shank has been thrust to its inner extreme of movement with respect to the barrel 56. Hence, the knobs 62 can be removed only by dismounting the entire latch and lock mechanism from the door 11 and inverting it, causing the plates 111 to drop out of the grooves 112.

The basket structure 13 is adapted to be received in a recess 116 which is let into the edge 29 of the door 11. This recess may easily be formed either by hand, or at the mill when the door is constructed. It should be understood that my invention contemplates providing doors with these recesses 116 with standard dimensions, so that my improved latch and lock may be mounted in operative position upon the door within a minimum amount of time and with a minimum expenditure of labor. The recess 116 is rectangular in configuration, and is complementary in shape to the basket structure 13, which, therefore, may be slipped into the recess 116 from the edge 29 of the door, with the escutcheon plates 96 and 97 separated sufficiently to permit them to overlap the edges of the recess 116. The recess 116 is of such depth that the outer end wall 17 of the basket 13 lies flush with the edge 29 of the door when the parts are thus assembled. The stay bolts 103 may then be tightened to clamp the escutcheon plates 96 and 97 against the faces of the door 11, thus securely anchoring the latch and lock device in operative position.

Inasmuch as the operation of each of the several parts of my latch and lock has been described hereinabove in conjunction with the description of the construction thereof, it is deemed unnecessary to include herein a further statement with respect to the manner in which the lock is employed.

Fig. 6 shows a slightly modified form of means for holding the bolt retracted while the door is open, and for automatically releasing the bolt when the door is closed. This modification is especially adapted for use in conjunction with a door 121 commonly provided upon an automobile. A bolt 122 is reciprocably mounted within a suitable basket structure 123, preferably of conventional design, and is provided with a notch 124 in its upper edge. A retaining plate 126 is provided with a projection 127 adapted to drop into the notch 124 when the bolt 122 is retracted. However, another projection 128 on the plate 126 is provided with a notch 129 in its under surface, and a rod 131 extending parallel with and immediately above the bolt 122 carries a cam 132 which cooperates with the notch 129 in such a manner that when the rod 131 is moved to the

left, as viewed upon Fig. 6, the plate 126 will be raised to lift the projection 127 out of the notch 124, whereupon a spring 133 is enabled to project the bolt 122 into latching position.

The rod 131 extends in the plane of the door entirely thereacross, and through the hinged edge 136 thereof, so that its projecting end 137 will engage the hinged edge of the door frame when the door closes, and thus cause the rod 131 to be pushed to the left, as viewed upon Fig. 6, at this time. Cooperative with the projecting end 137 of the rod 131 is an auxiliary rod 138 which extends downward from the rod 131 through the lower edge of the door 121. The lower edge of the door frame is provided with an inclined strike plate (not shown) with which the lower end of the rod 138 is adapted to engage when the door closes, pushing the rod 138 upwards. The upper end of the rod 138 is provided with an inclined surface 139 cooperative with an inclined surface 141, which is provided upon a collar 142 rigidly secured to the rod 131, so that this upward motion of the rod 138 will effect motion of the rod 131 to the left, as viewed upon Fig. 6. Hence, if the hinged mounting of the door 121 is such that a material space is left between the hinged edge 136 of the door and the associated edge of the door frame, when the door is closed, thereby preventing engagement of the end 137 of the rod 131 with the door frame, the engagement of the rod 138 with the bottom of the door frame will effect similar release of the bolt 122.

It is to be understood that the details of the invention as herein disclosed, are subject to alteration within the spirit or scope of the appended claims.

I claim:

1. In a door latch a basket structure, a bolt reciprocable longitudinally thereof, a shaft extending transversely of said basket structure and journaled therein, means interconnecting said bolt and shaft for retracting said bolt when said shaft is turned, a knob slidable axially onto each end of said shaft, means on said shaft engageable by each of said knobs for turning the shaft thereby, and gravity operated means for holding each of said knobs against axial displacement from said shaft.

2. In a door latch, an integral basket structure, a bolt reciprocable longitudinally thereof, a shaft extending transversely of said basket structure and journaled therein, means interconnecting said bolt and shaft for retracting said bolt when said shaft is turned, an escutcheon plate disposed upon each side of said basket structure and having a hole therein in alignment with said shaft, a knob associated with each of said plates and having a shank extending loose-

ly through the hole in the associated plate, each of said shanks being slidable onto the associated end of said shaft, means interlocking each shank with said shaft for rotary motion therewith, and a locking plate pivotally mounted on the inner face of each of said escutcheon plates and adapted to enter an annular groove in the associated shank to hold the associated knob against axial displacement from said shaft.

3. In a door latch, an integral basket structure, a bolt reciprocable longitudinally thereof, a shaft extending transversely of said basket structure and journaled therein, means interconnecting said bolt and shaft for retracting said bolt when said shaft is turned, an escutcheon plate disposed upon each side of said basket structure and having a hole therein in alinement with said shaft, means securing said escutcheon plates to said basket structure, said securing means being expandible to permit variation in the distance between said plates but holding said plates against movement within their respective planes with respect to said basket structure, a knob associated with each of said plates and having a shank extending loosely through the hole in the associated plate, each of said shanks being slidable onto the associated end of said shaft, means interlocking each shank with said shaft for rotary motion therewith, and a locking plate pivotally mounted on the inner face of each of said escutcheon plates and adapted to enter an annular groove in the associated shank to hold the associated knob against axial displacement from said shaft.

4. In a latch for a door having a recess let into an edge thereof, a basket slidable into said recess from said door edge, escut-

cheon plates mounted on said basket for adjustment perpendicularly to their planes to compensate for variation in the thickness of the door, said plates extending beyond the edges of said basket to embrace the faces of the door about said recess, and means for clamping said plates onto said door.

5. In a latch and lock, a reciprocably mounted bolt, a tubular shaft disposed perpendicularly with respect to said bolt and mounted for rotary movement, said tubular shaft having a socket transversely to its axis, a spring pressed detent in the socket and adapted to engage and lock said bolt against retracting movement, said detent having a bore, a locking shaft rotatable within said tubular shaft and passing through the bore of the detent, a cam on the locking shaft engaging the detent to retract the detent from said bolt, and means on each end of the locking shaft to rotate same.

6. In a latch and lock, a reciprocably mounted bolt having a recess adjacent its inner end, a tubular shaft disposed perpendicularly with respect to said bolt and mounted for rotary movement, said tubular shaft having a socket transversely to its axis, a spring pressed detent in the socket and adapted to engage the recess in said bolt to lock said bolt against retracting movement, said detent having a bore, a locking shaft rotatable within said tubular shaft and passing through the bore of the detent, a cam on the locking shaft for moving the detent out of the recess of the locking bolt, and means on each end of the locking shaft to rotate same.
